A. TAGGART.

PLASTERER'S DARBY.

APPLICATION FILED AUG. 21, 1918.

Patented June 24, 1919.

INVENTOR
ALFRED TAGGART

By Franklin H. Dough

Attorney

UNITED STATES PATENT OFFICE.

ALFRED TAGGART, OF BALTIMORE, MARYLAND.

PLASTERER'S DARBY.

1,307,939.

Specification of Letters Patent. Patented June 24, 1919.

Application filed August 21, 1918. Serial No. 250,835.

To all whom it may concern:

Be it known that I, ALFRED TAGGART, a citizen of the United States, residing at Baltimore, in the State of Maryland, have invented certain new and useful Improvements in Plasterers' Darbies; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in a darby for plasterers' use and it has for its object a simple and efficient device of this character cheaply constructed, which is made of separable parts 20 for convenience in packing and storing.

I am aware of the fact that darbies constructed of sheet metal adapted to be telescoped within a small compass have been heretofore constructed. I have found, however, that the best results are not obtained 25 by the use of a metal surface, and one of the essential objects of my invention is the provision of a darby, the body portion of which is constructed of wood, the sections 30 being separable and adapted to be confined within a small compass.

My invention consists of further various details of construction, combination and arrangement of parts which will be hereinafter 35 fully described, shown in the accompanying drawings and then specifically defined in the appended claim.

My invention is illustrated in the accompanying drawings which, with the letters of 40 reference marked thereon, form a part of this application and in which:

Figure 1 is a plan view of a darby constructed in accordance with my invention, the parts being shown as united and the 45 device in readiness for use.

Fig. 2 is an edge view of same.

Fig. 3 is a sectional view on line 3—3 of Fig. 1.

Fig. 4 is a sectional view on line 4—4 of 50 Fig. 1, and

Fig. 5 is a large detail showing the joint used in connecting the parts.

Reference now being had to the details of the drawings by numerals:

1 and 2 represent the sections of the body portion of the darby, the sections being of equal length, the inner ends of which have portions reduced in size as at 3, and which, when the device is prepared for use, are fitted within the metallic sleeve 4, the outer surfaces of which are flush with the front and rear surfaces of the sections 1 and 2. The face of the sleeve 4 is slightly roughened so as to conform to the degree of roughness of the surface of the wood to 65 which they are connected.

The sections 1 and 2 have recesses 3', 3' in their adjacent ends which latter telescope within a sleeve 4 apertured as at 4'. When the sections are end to end, a screw G is 70 passed through the apertures 4' and said recesses 3', and the end of the screw engages a nut 8 (see Fig. 3) seated in a countersunk recess 7 in the strip 5. Other screws similar to the screw 9 are formed through 75 the sections 1 and 2 and strip 5 and engage nuts 6 seated in a countersunk recess 7' in the strip 5.

10 designates the handle which serves as a pivotal point in the use of the tool. Upon 80 referring to Fig. 4 of the drawings, it will be noted that the rear face of section 1 is provided with an interiorly screw threaded chamber 11 within which is seated the screw threaded base 12 of the member 13, which 85 member is provided with an upward extension 14 which is seated within the opening provided for its reception in the longitudinal center of the handle, the free end of said extension 14 being rectangular in cross section and has its free end beveled to permit 90 of its being driven into the handle.

The lower end of the screw threaded base 12 is provided at its center with an extension 17 formed and serving as a screw 95 driver suitable for use in setting the screws 6—6 and for other purposes for which the same might be used. In order to protect the end of the darby, which when in operation is liable to injury from the mortar 100 board, a metallic band 20 is provided.

What I claim to be new is:

A darby, comprising two sections, the adjacent ends of which are reduced in size, a

shell within which said reduced portions of telescope, a locking block fastened to said sections and abridging the meeting ends thereof and said shell, a bolt passing through 5 registering apertures in the shell and engaging said block, a nut engaging said bolt and countersunk in a recess in the block.

In testimony whereof I hereunto affix my signature in presence of two witnesses.

ALFRED TAGGART.

Witnesses:

GUSTAVUS WERBER,
FRANKLIN H. HOUGH.
